UNITED STATES PATENT OFFICE.

CARL B. TODD, OF RICHMOND, KENTUCKY.

RECEPTACLE.

Application filed January 10, 1924. Serial No. 685,438.

To all whom it may concern:

Be it known that I, CARL B. TODD, a citizen of the United States, residing at Richmond, in the county of Madison and State 5 of Kentucky, have invented certain new and useful Improvements in a Receptacle, of which the following is a specification.

My present invention relates to receptacles and more particularly to cuspidors 10 wherein a well is arranged within a housing and means is provided whereby the well may be moved outwardly of the housing when desiring to use the same.

The primary object of the invention is to 15 provide an improved cuspidor possessing sanitary features in that the same will remain covered at all times except at the short period of time required for actual use.

Another object is to provide a cuspidor 20 which may be placed in any out of the way place, as under an article of furniture or such, and one having a well which may be readily removed and cleaned; yet possessing features whereby accidental discharge of the 25 contents will be eliminated.

Other objects of my invention will appear in the following detailed description, taken 30 in connection with the accompanying drawings, forming a part of this specification, and in which drawings,

Figure 1 is a top plan view of the receptacle, parts being broken away to disclose certain details of construction.

Figure 2 is a front elevation of the receptacle, parts being broken away to disclose further details.

Figure 3 is a vertical sectional view taken on the line 3—3 of Figure 1 and looking in the direction of the arrows.

Figure 4 is a top plan view of the movable well.

Figure 5 is a transverse section taken on the line 5—5 of Figure 4.

Figure 6 is an enlarged fragmentary sectional view showing the method of mounting the rollers upon which the well is adapted to roll.

Figure 1 is a detail sectional view of a buffer used in conjunction with the operating means for preventing too sudden return 50 of the well to a closed position.

Referring to the drawings in detail, wherein similar reference characters designate corresponding parts throughout the 55 several views, the letter A designates an improved receptacle embodying a housing B

and a movable well C; D an operating means for imparting movement to the well C and E buffer means associated with the movable well C for preventing quick movement of 60 the well to a retarded position.

The housing B which may be formed of sheet metal finished in any desirable manner, comprises side walls 10 and 11, rear wall 12 and top and bottom walls 13 and 14 respectively. The front of the housing B is open so as to permit of the well C to move into and out of the housing by the operating means D. Feet 15 are provided on the housing B in order that the housing may be 65 secured in position at any desirable place for preventing accidental tipping of the same.

Sets of rollers 16 and 17 carried by the side walls 10 and 11 respectively, are adapted to bear against the top and bottom walls of the well C for permitting of easy movement of the well C and also prevent tipping of the well when ejected from the housing B. As shown in Figure 6, the set of rollers 70 17 may have their bearings 18 secured in a supporting bracket 19, as the rollers 17 are spaced from the side wall 11 so as to engage the well C which is also spaced from the wall 11 for providing a space for the 75 operating means D.

The well C which is adapted for movement into and out of the housing B, is provided with a plurality of vertical, longitudinally extending baffle plates 20 having 80 openings 21 provided in the lower edges thereof for permitting of even distribution of the contents of the well. These baffles 20 are provided in order to prevent splashing of the contents within the well as the well is 85 being moved. The upper and lower ends of these baffles 20 are bent at right angles as at 22 for securing the baffles in place, and for a purpose to be later set forth. An elongated opening 23 provided in the top 90 wall 24 of the well C and at the forward portion thereof, has positioned therebelow, a plurality of staggered deflecting plates 25 for preventing escapement of any of the contents within the well when being 95 moved. A container 26 for holding a disinfectant which is positioned beneath one of the plates 25 is provided with a wick 27 for allowing the disinfectant to enter the well C. If desired, any other suitable means 100 such as a valve or pump may be employed 105 of allowing the disinfectant to enter the

well. A removable cover portion 28, which is provided for permitting of the cleaning of the well, may be securely held in place by wing nuts or the like 29 which screw 5 into the upper right angular flange 22 of one of the baffle plates 20. The front plate of the well may have depressions 30 formed therein for providing a means for handling the well when removed from the housing 10 B. A roller 30 may be secured to the lower rear corner of the well C intermediate the rollers 16 and 17 for supporting the rear end of the well.

The operating means D for ejecting and 15 retracting the well C comprises a bell crank lever 32 provided with a stub shaft 33 pivotally mounted in the lower portion of the end wall 11. This stub shaft 33 extends through the end wall 11 and has secured to the outer 20 end thereof, as by a pin or the like, an operating lever 34; the free end of which extends forwardly past the front wall of the receptacle A. A stop pin 35 may also be provided in order to limit the movement of the 25 operating means when the well C is being ejected from the housing B. The free end of the arm 36 of the bell crank lever 32, has pivotally connected thereto a link 37 which extends forwardly and has its forward end 30 pivotally and detachably connected to the end wall 38 of the well C at a point approximately near the forward edge thereof. The forward end of the link 37 may be pivotally connected to the well C as by a trunnion 39 35 carried by the end wall 38, and held against displacement by a cotter pin or the like 40. It will be noted that when the well C is ejected from the housing B, that the well may be readily and conveniently disconnected 40 from the link 37, as the connecting means will now be clear of the housing B. A coil spring 41, one end of which is secured to the free end of the arm 36 and the other end to the housing B, serves as a means for 45 extracting the well C when the operating lever 34 is released.

The buffer means E comprises a cylinder 42 being open at one end and provided at its opposite end with an arm 43 adapted for 50 pivotal connection with a pin 44 carried by the end wall 11. A plunger 45, movable in the cylinder 42, has its outer end pivotally connected to the free end of the arm 46 of the bell crank lever 32. An adjustable air 55 escapement screw 47 is provided in the cylinder 42 at the closed end thereof for permitting of the regulating of the operating means D. It can therefore be seen that by so providing the buffer means E, the well C will 60 not jar when being returned to a retarded position which would result in a possible spilling of the contents of the well.

It will be noted from observing Figure 1 65 of the drawings, that all of the operating means except the operating lever 34 is posi-

tioned inwardly of the housing B and therefore provides a neat appearing outer surface for the receptacle.

While the device as described has been limited to a cuspidor of novel construction, 70 it is to be understood that by a slight alteration of the well, the receptacle will be found to be equally well efficient for use such as a receptacle for garbage, refuse, shoe shining materials and also used in stores for holding 75 various commodities.

As the receptacle is not limited to use when placed upon the floor, the operating lever 34 may vary slightly in construction 80 in order to permit of the operation of the well as by grasping the lever with the hand.

Various changes in detail may be made without departing from the spirit or scope of my invention; but,

I claim:

1. The combination with a housing and a well arranged for sliding movement in said housing, of operating means for the well comprising means for ejecting and retracting the well with respect to the housing, and means associated with the housing and well for retarding quick movement of the well to a retracted position throughout the entire inward movement of the well. 90

2. The combination with a housing and a well arranged in said housing, of means for ejecting the well from said housing comprising a lever pivotally connected to said housing, a link pivotally connected at one end to the arm of said lever and having its other end pivotally connected to said well and means connected to said lever for imparting movement thereto; means for retracting the well to a position within said housing and means associated with the housing and well for retarding quick movement of the well to a retracted position. 95

3. The combination with a housing and a well arranged in said housing, of means for ejecting the well from said housing comprising a bell crank lever pivotally connected to said housing, a link pivotally connected at one end to one arm of said bell crank lever and having its other end pivotally connected to said well and means connected to said bell crank lever for imparting movement thereto; means for retracting the well to a position within said housing, and means associated with the other arm of said bell crank lever for retarding quick movement of the well to a retracted position. 110

4. The combination with a housing and a well arranged in said housing, of means for ejecting the well from said housing comprising a bell crank lever positioned inwardly of one end wall of the housing and having its pivotal shaft extending outwardly through the end wall, a link pivotally connected at one end to one arm of said bell crank lever and having its forward end 125 130

- pivotally and detachably connected to an end wall of said well at a point near the forward edge thereof, and an operating lever secured to the outer end of the pivotal shaft 5 of said bell crank lever for imparting movement thereto; a coil spring having one end connected to the above mentioned arm and having its other end connected to said housing for retracting the well to a closed position, and means associated with the other arm of said bell crank lever for retarding quick movement of the well to a retracted position.
5. The combination with a housing and a well arranged in said housing, of means for ejecting the well from said housing comprising a bell crank lever pivotally connected to said housing, a link pivotally connected at one end to one arm of said bell crank lever and having its other end pivotally connected to said well and means connected to said bell crank lever for imparting movement thereto; means for retracting the well to a position within said housing and buffer means 20 for the well comprising a cylinder being open at one end and provided at its closed end with an adjustable air escapement screw, said cylinder to be pivotally connected at its closed end to an end wall of said housing,
- and a plunger pivotally connected to the other arm of said bell crank lever and operable in the cylinder for retarding quick movement of the well to a retarded position. 30
6. In a receptacle, the combination with a housing, of a well provided with an elongated opening in the forward portion of the top wall thereof, arranged in said housing and provided with a plurality of transversely extending intercommunicating baffle plates, staggered deflecting plates positioned 35 beneath the opening in said well, and a removable cover portion rearwardly of said elongated opening, means for ejecting and retracting the well with respect to the housing whereby when said well is in an ejected 40 position, the opening will be disposed free of the housing and said cover portion will be concealed beneath the top wall of the housing, and means operable upon the well for retarding quick movement of the well to 45 a retracted position. 50

In testimony whereof I affix my signature in presence of two witnesses.

CARL B. TODD.
